UNITED STATES PATENT OFFICE.

ARTHUR C. MASON, OF HAWTHORNE, NEW JERSEY.

STOP-MOTION MECHANISM FOR WARPING MACHINES.

Application filed September 2, 1922. Serial No. 585,924.

To all whom it may concern:

Be it known that I, ARTHUR C. MASON, a citizen of the United States, residing at Hawthorne, in the county of Passaic and State of New Jersey, have invented certain new and useful Improvements in Stop-Motion Mechanisms for Warping Machines, of which the following is a specification.

This invention relates to means for detecting the breaking or slackening of a thread or threads of a warp while being advanced, as in warping, for example, in connection with which the invention is herein in fact illustrated and described. The principal objects of the invention are to provide means of this class which shall be compact and simple in construction, reliable in operation, and adapted to facilitate the operative arrangement in reference thereto of the warp as a whole or of any individual thread on slackening or breakage and consequent repair thereof. The invention contemplates also associating with the detecting mechanism means for stopping the advance of the warp automatically when breakage or slackening of any thread occurs.

In the drawings,

Fig. 1 is a front elevation of a creel for a warping machine provided with the improved mechanism, partly in section;

Fig. 2 is a vertical sectional view on line 2-2, Fig. 1;

Fig. 3 is a right side elevation of what is shown in Fig. 1;

Fig. 4 is a plan of a detail;

Fig. 5 is a front elevation on a larger scale of the detecting members and of a rotary structure cooperative therewith to stop the advance of the warp;

Fig. 6 is a vertical section of what is shown in Fig. 5;

Fig. 7 is a plan of the detecting members, showing in section the structure in which they are supported;

Fig. 8 is a plan of the warp, showing the detectors in horizontal section and one detector released by breakage of the corresponding thread;

Fig. 9 is a diagrammatic illustration of the means whereby, on breakage or undue slackening of a thread, the advance of the warp may be stopped; and

Fig. 10 shows a detail.

a designates the creel for a warping machine and *b* the usual skewers arranged thereon for the reception of the rotary bob-

bins *c* from which the warp is taken. *d* is the bar of the creel over which the warp extends from the bobbins and *e* is the reed through which the warp is then passed in the usual way.

To the side uprights of the creel are bolted the upstanding brackets *f*. These are rigidly connected by two horizontal channeled rails *g* somewhat spaced from each other. Each rail has a horizontal series of holes *g'* formed in the basal portions of its two upright walls so that each hole in the one wall is directly opposite a similar hole in the other wall, each two such opposed holes forming a bearing for the pivoted detector to be described. The outer wall of each rail has a series of slits or saw-cuts *g*² formed in its top edge, and the inner wall has a series of openings *g*³ (appreciably wider than the slits and opposite the same).

Detectors in the form of levers are provided as follows: Each detector includes a rectangular block or body *h*, a pin or leg *h'* projecting downwardly therefrom, a pin or leg *h*² projecting upwardly therefrom, and a laterally extending trunnion *h*³. The detectors are arranged between the two rails *g* (Fig. 6) and have their trunnions journaled in the aforementioned holes *g'*, their pins or legs *h*² and *h*¹ projecting respectively up and down. Each detector has set in a slit in its body *h* a spring blade *h*⁴ which plays freely in the corresponding notch *g*³ but is fixed at its free end in the corresponding saw-cut *g*², the spring normally tending to hold the detectors vertical, as indicated by the one which is in that position in Fig. 5. In the construction being explained by way of example there are two sets of detectors, one carried by each rail *g*; and those of one set are so arranged that the pins or legs *h'* of one set are staggered with reference to those of the other (Fig. 8). This arrangement will usually be found necessary in order to accommodate all the threads of an ordinary warp. The warp is indicated at *A* and when it is subjected to tension, as by the reel of a warping machine (only the drive and idle pulleys of which are shown, Fig. 9) pulling against the resistance afforded by the bobbins *c*, its various threads hold the several detectors or detector levers tilted (Fig. 5) until one of the threads breaks or unless one or more of the threads becomes unduly slack, whereupon the detector will be returned by the tension of its

105

100

110

spring blade h^4 to the vertical position. The operative placement of the warp in reference to the several detectors, as well as the entering of a slack thread or a pieced thread 5 that has been broken, may be performed with complete facility because of the comb-like arrangement of the thread-engaging portions (here the pins or legs h' of the detectors). h^5 is simply a cover plate arranged 10 under and secured to the rails g and slotted to receive the detector legs or pins h' (Figs. 5 and 6).

With the detecting mechanism thus afforded I prefer to provide means for stopping the advance of the warp when any detector is released by a thread and so is moved by its spring blade to abnormal position. Therefore, in the brackets f is journaled a 20 rotary structure consisting of a shaft i on which are keyed, spaced from each other, a series of stop-wheels j . Each two legs, h^2 of two detectors, one in each series, are arranged approximately in the same line parallel with the warp, and there is a stop- 25 wheel for every two such detectors, the spaces between the stop-wheels being sufficiently wide so that when the detectors are in the normal or tilted positions (Fig. 5, excepting as to one of the detectors) the

30 stop-wheel structure may rotate without interference by the detectors. When a thread breaks or becomes abnormally slack and its detector assumes the upright position its leg h^2 stands in the path of the corresponding 35 stop-wheel, so that the rotation of the stop-wheel structure is checked. On the shaft i of said structure is freely revoluble a beveled pinion k and splined on the shaft is a collar l which is held against the hub of the 40 pinion by a spring m , one of the members k, l having a notch and the other a tapered tongue or lug as indicated at n in Fig. 9 and they thereby forming a clutch of the type which, member k being suitably driven and 45 so acting through member l to rotate the stop-wheel structure, will collapse or yield if the rotation of said structure is checked while the member k continues being rotated. Member k meshes with the beveled pinion o on the upper end of a shaft p journaled in 50 the side of the creel, the lower end of said shaft carrying another beveled pinion q meshing with a beveled pinion r which is rigidly connected to rotate with a sprocket- 55 wheel s adapted to be driven by a chain t from some rotating part of the warping machine. Let u represent a part of the rotary train of a warping machine, which causes advance of the warp, u being here the fast or driving pulley of the machine adapted to be driven as usual from a belt v ; w is a loose pulley concentric with pulley u ; x is a shifter for the belt v , its supporting 60 shaft x' being arranged to slide in suitable bearings y and urged in the direction to

shift the belt from the fast to the loose pulley by a spring z interposed between one of said bearings and a head x^2 on said shaft, its movement in said direction being normally opposed by a pawl 2 arranged to engage said head. This pawl is connected by a flexible connection 3 with a bell-crank lever 4 pivoted in one of the brackets f and having one arm engaged in a peripheral groove in the clutch collar l . When a thread breaks or 70 unduly slackens and the corresponding detector stops the rotation of the stop-wheel structure and the clutch is disestablished, as explained, the consequent shifting of member l acts, through the lever 4 and connection 3 , to trip the pawl 2 . This allows the spring z to shift the shifter and consequently the belt from the pulley u to the pulley w , wherefore the advance of the warp ceases. 80

It is desirable that the checking of the advance of the warp should take place gradually, so that none of the bobbins will overrun and produce slackness in the corresponding thread. Wherefore I cause the shifting 90 of the shifter x to take place slowly under the pressure of the spring z by opposing a resistance thereto in the form, say, of a dash-pot 5 .

When the necessary repair or adjustment 95 of the thread that caused stopping of the machine has been effected, the operator can start the machine again by depressing a foot treadle 6 which through the illustrated connection 7 resets the shifter in position to establish the belt on the fast pulley and be there locked by the pawl 2 .

Fig. 8 shows at 8 a part (to wit, one of the transverse warp-supporting slats or rails) of the warping machine reel, which latter 105 coacts, when rotating to advance the warp, with the resistance afforded by the bobbins c to keep the warp taut, though each thread may have a slight bend therein due to the pressure of the detector thereagainst. 110

I preferably provide means which obtains a slip hold on the stop-wheel structure at each of the several points in its rotation corresponding to the spacing around its axis of the stopping or acting faces j' of its abutment members formed by its stop-wheels. For example, the shaft i may have fixed thereon a wheel 9 having in its periphery notches $9'$ spaced the same as said faces of each stop-wheel, and peripherally engaging 120 this wheel is a roller 10 journaled in a slide 11 guided in one of the brackets f and urged toward the wheel by the spring 12 . The roller being engaged in a notch $9'$ the connection thus established is insufficient to resist the slip-clutch-connection at n when the tongue is engaged in the recess forming this clutch-connection n ; but when the tongue is disengaged from said recess and opposes the smooth side surface of collar l the con- 125

65 130

nection afforded by the engagement of roller 12 in a notch 9' is sufficient to overcome the mere friction between the tongue and said side surface of collar 7. Now when a faller 5 stops the stop-wheel structure the roller 10 will have begun to be cammed by wheel 9 out of the notch 9' with which the roller then registers, but as soon as the clutch is disestablished the (spring-pressed) roller 10 will turn the stop-wheel structure back until said roller is re-seated in the notch. This will leave the stop-wheel clear of the 15 end of the pin h^2 of the detector which contacted therewith, so that it will not be prevented from assuming the tilted position when its thread A is re-tautened. Again, if the machine stops with the clutch disestablished, the tongue of the clutch-connection n being in contact with the smooth side 20 face of collar 7, the slip-hold means 9—10 will hold the stop-wheel structure against turning, when the machine is started by pressing on treadle 6, until said tongue can rotate sufficiently to reestablish the clutch 25 connection and thus allow collar 7 to assume its normal position and so permit pawl 2 to resume its locking relation to the shifter.

Having thus fully described my invention, what I claim as new and desire to secure by 30 Letters Patent is:—

1. In combination, with mechanism to advance a warp longitudinally and meanwhile maintain the same taut, a support, and detectors having free ends all projecting in 35 substantially the same direction, said detectors being movable in the support back and forth laterally of the warp and respectively engaged with the threads of the warp, each detector being normally urged in one direction 40 and held by the corresponding thread against such movement and the support affording clearance for shifting the constituent threads of the warp in between and out from between the detectors.

2. In combination, with mechanism to advance a warp longitudinally and meanwhile maintain the same taut, a support, and detectors having free ends all projecting in 45 substantially the same direction, said detectors being movable in the support back and forth laterally of the warp and alternating with and respectively bearing sidewise against the threads of the warp, each detector being normally urged in one direction 50 and held by the corresponding thread against such movement and the support affording clearance for shifting the constituent threads of the warp in between and out from between the detectors.

3. In combination, with mechanism to advance a warp longitudinally and meanwhile 55

maintain the same taut, a support, and detectors each movable in the support back and forth laterally of the warp and alternating with and respectively bearing sidewise 65 against the threads of the warp, each detector being normally urged in one direction and held by the corresponding thread against such movement and said detectors forming a comb-like series and the support 70 affording clearance for shifting the constituent threads of the warp in between and out from between the detectors.

4. In combination, with means to advance a warp longitudinally and meanwhile maintain the same taut, a support, detectors each movable in the support back and forth laterally of the warp and respectively engaged with the threads of the warp, and plate 75 springs each engaged at one end with a detector and at the other with the support and normally urging the detector in one direction, the detectors being held by the warp against the tension of the springs.

5. In combination, means to advance the 80 warp, means to exert resistance on the warp and thus coact with the first means to maintain the warp taut, a support, a rotary structure journaled in the support on an axis extending crosswise of the warp and including 85 a series of stopping members arranged longitudinally of the axis of said structure and spaced from each other, yielding means to transmit rotation to said structure, and detectors each movable back and forth laterally of the warp and respectively engaged with the threads of the warp, each detector projecting between two of said members and normally urged in one direction into the 90 rotary path thereof and held by the corresponding thread against such movement.

6. In combination, mechanism to advance a warp longitudinally and meanwhile maintain the same taut, a support, a rotary structure journaled in the support and including 100 abutment members arranged longitudinally of its axis and spaced from each other, detectors movable back and forth respectively into and out of and normally urged into the paths of said members, the warp threads being adapted to normally hold said detectors 105 respectively out of said paths, means having a slip-clutch connection with said structure to rotate the same, and means, on a thread allowing the corresponding detector 110 to assume a position in the path of an abutment member and on consequent slipping of said clutch connection, to rotate backwardly 115 said structure to clear said detector.

In testimony whereof I affix my signature. 120

ARTHUR C. MASON.
